(57) **CLAIM**

The ornamental design for an annular flux collector for a valve body, as shown and described.

DESCRIPTION

FIG. 1 is a top view of an annular flux collector in accordance with the present teachings.

FIG. 2 is a bottom view of the annular flux collector of FIG. 1.

FIG. 3 is a back view of the annular flux collector of FIG. 1.

FIG. 4 is a front view of the annular flux collector of FIG. 1.

FIG. 5 is a side view of the annular flux collector of FIG. 1.

FIG. 6 is an opposite side view of the annular flux collector of FIG. 1.

FIG. 7 is a perspective view of the annular flux collector of FIG. 1; and,

FIG. 8 is an exploded perspective view of the annular flux collector of FIG. 1.

The broken lines showing portions of the annular flux collector and showing the valve body extension form no part of the claimed design.
